PLIER WRENCH

Ted Neff, 20975 Shamrock Ave., San Bernardino, Calif.

Filed Mar. 28, 1963, Ser. No. 74,168

Term of patent 14 years

(Cl. D54—13)

FIG. 1 is a side elevational view of a plier wrench showing my new design;

FIG. 2 is an elevational view on one edge view thereof;

FIG. 3 is an elevational view of the other edge thereof;

FIG. 4 is a fragmentary perspective view of the head of the plier wrench.

The undisclosed side is identical to the side shown.

I claim:

The ornamental design for a plier wrench, as shown and described.
